UNITED STATES PATENT OFFICE.

DAVID T. OWEN, OF CLEVELAND, OHIO.

BED AND COUCH.

Application filed February 9, 1921. Serial No. 443,529.

To all whom it may concern:

Be it known that I, DAVID T. OWEN, a citizen of the United States, residing at Cleveland, in the county of Cuyahoga and State of Ohio, have invented certain new and useful Improvements in Beds and Couches, of which the following is a specification.

My invention relates to an improvement in beds and couches, and more particularly in 10 spring seats for beds and couches, the object being to provide a spring seat which is particularly adapted to co-act with a flat flexible spring-bottom so that a person may be supported in a comfortable sitting position and 15 state of equilibrium at any point on the seat and especially at or near the ends where the tendency of the flexible spring bottom is to unbalance a person and make upright sitting strained and uncomfortable.

20 In the accompanying drawing, Fig. 1 is a front view and section of a couch and spring seat constructed according to my invention. Fig. 2 shows the spring-bottom deflected under the weight of a person sitting 25 on the seat but with the counter-poising in the seat acting to hold the person upright and balanced. Figs. 3 and 4 are diagrammatic views illustrating the action of the customary flat flexible spring bottom used in 30 beds and couches generally.

This invention is a development arising from certain objectionable conditions inherent in couches and davenport beds having flat spring-bottoms, comprising a network of wire 2 stretched within a frame 4 by coiled 35 extension springs 3 affixed to the opposite ends of the network. When a person is seated on this type of spring-bottom midway between its ends he is supported in a 40 comfortable upright position because the angle of deflection of the spring-bottom from a horizontal line is exactly the same on opposite sides of the sitter, see Fig. 4. On the other hand when a person is seated 45 near either end of the spring-bottom the angle of deflection is unequal on opposite sides of the sitter and the shorter sloping surface is of steeper pitch and the coiled springs at that end are under greater tension 50 and the action stiffer than the longer stretch of spring-bottom, and this condition unavoidably causes the body of the sitter to slant to one side and become unbalanced, see Fig. 3. This posture is unnatural and a person in that position is constantly seeking to 55 maintain his equilibrium and is under a con-

stant strain. To obviate such a condition and establish a perfect counter-poise without effort on the part of a person sitting at either end of the spring-bottom, I have devised a spring seat 5 which is adapted to rest upon the flat spring-bottom and which comprises a series of compression springs 6, 7 and 8 of different power arranged successively from each end in regular gradations, the lighter or less powerful springs being at the ends of the seat and the heavier and stronger springs more remote therefrom and nearer the center or middle of the seat. However, it is not absolutely essential that 70 the graduated arrangement of the springs shall extend from each end to the very center of the seat. In fact the central portion 9 of seat 5 may be merely padded or stuffed with any suitable cushioning material, such 75 as hair, felt or cotton, and only the end portions of the seat equipped with springs to counterpoise the sitter.

The counterpoising springs used in the seat may be relatively small and numerous 80 and connected and confined within a cover of upholstering in any practical way known to skilled upholsterers, and the built-up pad or seat 5 may be made a permanent part of the flat spring-bottom or it may be made and sold separately for use with such flat spring bottoms.

What I claim, is:

1. A bed or couch frame having a flat flexible spring-bottom stretched horizontally 90 therein, in combination with a cushioning seat comprising relatively small and numerous counterpoising springs within and relatively near the end portions thereof adapted to maintain a person sitting at either end of said seat and spring-bottom in a state of 95 equilibrium.

2. A bed or couch having a flat flexible spring-bottom with helical supporting springs at each end horizontally stretched 100 therein, in combination with a seat upon said spring-bottom having numerous small springs of different power arranged in graduated order its relatively near opposite ends adapted to maintain the equilibrium of a 105 person sitting upon the end portion of said seat and spring-bottom.

3. An upholstered pad or seat for beds and couches having flat flexible spring-bottoms, comprising numerous small graduated 110 compression springs incorporated within the extremities thereof.

4. A pad or seat for beds and couches, comprising a central padded portion of cushioning material and end portions having springs incorporated therein, successively 5 more resilient relatively near and toward the end of said pad or seat.
5. A pad or seat for beds and couches, comprising separate helical springs incorporated within and relatively near each end

portion and of graduated strength and arranged closely adjacent each other in graduated order to offer increasing resistance at successively different points from the ends toward the center of said pad or seat.

Signed at Cleveland, in the county of 15 Cuyahoga, and State of Ohio, this 1st day of February, 1921.

DAVID T. OWEN.
